UNITED STATES PATENT OFFICE

2,318,913

WATER HEATER

Loyd I. Aldrich, Wyoming, Ill.

Application February 24, 1941, Serial No. 380,299

6 Claims. (Cl. 122—32)

My invention relates to a water heater, particularly one for heating domestic hot water in a vertical type boiler.

One object of the invention is to provide a domestic water coil which is readily renewable and installable relative to a vertical flue type of boiler in such manner that the coil has considerable volume and extends throughout a considerable extent of the space within the boiler.

Another object is to provide a water heating tube in the form of a coil which may be rotated during installation so as to surround the flues of a boiler and which requires only a relatively narrow arcuate slot for insertion of the coil into installed position.

Another object is to provide a coil which may be inexpensively formed of copper or Monel metal tubing, or the like, and so wound and arranged that it may be installed in a successive manner throughout its length without its installation being interfered with by the flues of the boiler.

A further object is to provide a coil which is initially anchored to a cover plate for an opening in the tank of the boiler and which is installed by inserting the coil through the opening and finally securing the cover plate in position over the opening, with a gasket interposed between the cover plate and the water tank.

Other objects, purposes and characteristic features of the present invention will be in part obvious from the accompanying drawing and in part pointed out as the description of the invention progresses. In describing the invention in detail, reference will be made to the accompanying drawing in which like reference characters designate corresponding parts throughout the several views, and in which—

Figure 1 is a vertical partially sectional view through a water heater embodying my invention;

Figure 2 is a horizontal sectional view on the line 2—2 of Figure 1;

Figure 3 is a sectional view of a portion of the boiler showing the manner of installing my water coil therein, and

Figure 4 is an enlarged sectional view on the line 4—4 of Figure 2.

On the accompanying drawing I have used the reference character B to indicate generally a water heating boiler. The boiler B includes a water tank T having an end member 10. The end member may be welded on the tank T.

The boiler B further includes a combustion chamber 12 with which a suitable oil burner or the like (not shown) may be associated. Heat-

ing flues 13 extend upwardly from the combustion chamber 12 through the end member 10 and communicate with a chamber 14 adapted to convey the exhaust gases to a stack 15.

5 My domestic hot water heating coil is indicated generally at C and comprises an inlet tube 16 and an outlet tube 17. The tubes 16 and 17 may be made of copper tubing or the like and constitute a doubled coil by brazing or otherwise 10 suitably securing a U fitting 18 at their lower ends. The tubes 16 and 17 are wound in the form of a coil of the desired diameter, the coil having its windings initially close together for compactness in shipping, as illustrated in the 15 upper part of Figure 3.

Attached to the coil C at the factory is a cover plate 19, the method of attachment comprising, by way of example, fittings 20. The tubes 16 and 17 adjacent their upper terminal ends are packed 20 relative to the fittings 20 by brass ferrules or sealing rings 21 and ferrule nuts 22. The terminal ends of the tubes 16 and 17 may be flared, as indicated at 23, and provided with connecting nuts 24 for connecting them with fittings 25 on 25 a cold water inlet pipe 26 and a hot water outlet pipe 27, respectively. Obviously, any other type of connection may be made at these points.

The cover plate 19 is provided for an arcuate slot 28 in the end plate 10 of the tank T. It may 30 be secured thereto as by cap screws 29 and sealed relative thereto as by a gasket 30. In this manner the cover plate is removable for replacing the coil C, as will hereinafter appear. The tubes 16 and 17 of the coil C may be secured together as 35 by brazing at spaced points, indicated at 31.

The coil is installed in the manner shown in Figure 3. The lower end of the coil is opened up 40 sufficiently to permit insertion of the return fitting 18 through the arcuate slot 28, and thereafter the coil C may be rotated clockwise and it will assume a position in the tank T surrounding the tubes 13 as it is installed, as indicated by the arrows 31a in Figure 3. The final position of the coil C will be as illustrated in Figure 1 when it is 45 filled with water for operation.

It is thus obvious that the coil C may be readily installed initially after the entire assembly of tank T, combustion chamber 12 and heating flues 13 has been fabricated as by welding or the like. Subsequently the coil C may be removed and replaced with another one after the tank T has been installed in an outer casing 32 with the usual insulating material 33 surrounding the tank. The casing 32 has a top member 34, which of 50 course could be provided with a suitable remov-

able cover plate 35 to gain access to the cover plate 19.

The formation of the tubes 16 and 17 into a coil permits ready installation of the coil without having to open the entire end 10 of the tank T. The space between the tube 13 and the tank T and also between the combustion chamber 12 and the tank T and between the tubes themselves, is filled with a heat conducting medium 36, such as water containing a rust inhibitor which prevents rust from attacking the steel of the tank, combustion chamber and tube. The water 36 serves as a heat conductor from the combustion chamber and flues to the coil C and, due to the rust inhibitor contained in it, prevents any tendency of the outside of the tubes 16 and 17 to rust if made of a metal containing iron or steel.

While I have shown a particular embodiment of my invention, it will be understood of course that I do not wish to be limited thereto since many modifications may be made, and I therefore contemplate by the claims appended hereto to cover any such modifications or substitutions of mechanical equivalents as fall within the true spirit and scope of my invention without sacrificing any of its advantages.

I claim as new and desire to secure by Letters Patent of the United States:

1. In a water heater, a vertically disposed water tank, vertically disposed heating flues therein, a water coil surrounding said flues, said coil having a formation doubled back on itself, an arcuate slot in the top end of said water tank at a distance from the center greater than that of the outermost heating flue permitting reception of said coil by a rotating movement to dispose the coil in a position surrounding said flues and spaced therefrom, a cover plate for said slot having water-tight connection with said tank adjacent and surrounding said slot, said water coil adjacent its terminal ends being sealed relative to said cover plate.

2. In a water heater, a water tank, heating flues extending longitudinally thereof, a water coil doubled back upon itself and wound around said flues, a slot in the end of said water tank between the periphery thereof and the outermost flue permitting reception of the doubled end of said coil for introduction of the coil to its final position by rotating it around said flues, a cover plate for said slot having a water-tight connection with said tank, said water coil adjacent its terminal ends being sealed relative to said cover plate.

3. In a device of the class described, a tank, heating flues therein, a coiled water conducting tube surrounding said flues, an arcuate slot extending only part way around the end of said

tank located between the periphery thereof and the flues permitting reception of said coil by a rotating movement to dispose the coil around said flues, and a cover plate for said slot having water-tight connection with said tank adjacent and surrounding said slot, said water coil being carried by said cover plate.

4. In a water heater, a vertically disposed water tank, vertically disposed heating flues therein, a looped water coil surrounding said flues, the two stretches of said coil being connected together at spaced points along the coil, an arcuate slot in the end of said water tank located between the periphery thereof and the portion occupied by the flues permitting reception of said coil by a rotating movement to dispose the coil in a position surrounding said flues, a cover plate for said slot overlapping the edge thereof, said cover plate being bolted to said tank end adjacent said slot with a gasket interposed between the cover plate and the tank end, a pair of fittings in said cover plate, the two stretches of said coil adjacent the terminal ends thereof extending through said fittings, packed connections between said fittings and said stretches of said coil, and fittings on the terminal ends of said coils for connecting them with inlet and outlet water pipes.

5. A device of the class described comprising a tank, heating flues therein, a looped helical water coil positioned in said tank to surround said flues, an arcuate opening in the end of said tank extending only part way around permitting reception of said coil therethrough and into the tank adjacent said flues, an arcuate cover plate for said opening and bolted to said tank end adjacent the opening with a gasket interposed between the cover plate and the tank end, a pair of fittings in said cover plate, the two stretches of said coil adjacent the terminal ends thereof extending through said fittings, and packed connections between said fittings and said stretches of said coil.

6. In a water heater, a tank, a group of heating flues therein, a helical water coil surrounding said flues, an opening in a wall of said water tank adjacent one end of said group of flues and permitting reception of said coil to a position for surrounding said group of flues by rotation of said coil therearound, a cover plate for said opening overlapping the edge thereof, means for securing said cover plate to said tank end and for sealing it relative thereto, a pair of fittings in said cover plate, said coil, adjacent its terminal ends, extending through said fittings and being sealed relative thereto, and fittings on the terminal ends of said coils for connecting them with inlet and outlet water pipes.

LOYD I. ALDRICH.
